UNITED STATES PATENT OFFICE.

JEAN BAPTISTE BELANGER, OF MONTREAL, QUEBEC, CANADA.

DESIGN FOR A LAMP STAND.

Application filed August 24, 1927. Serial No. 23,196. Term of patent 3½ years.

To all whom it may concern:

Be it known that I, JEAN BAPTISTE BELANGER, a subject of the King of Great Britain, residing at 1816 Visitation Street, in the city of Montreal, Province of Quebec, Dominion of Canada, have invented a new, original, and ornamental Design for Lamp Stand, of which the following is a specification, reference being had to the accompanying drawing, forming part thereof.

The figure is a perspective view of a lamp stand showing my new design, with the upper part broken away and the conventional shade shown in dotted lines.

I claim:

The ornamental design for a lamp stand, as shown.

JEAN BAPTISTE BELANGER.
